G. F. DICKS

RAILROAD TIE SPACER

Filed July 7, 1927

Inventor

G. F. Dicks

By A. Randolph, Jr.

UNITED STATES PATENT OFFICE.

GEORGE F. DICKS, OF HOMEDALE, IDAHO.

RAILROAD-TIE SPACER.

Application filed July 7, 1927. Serial No. 204,037.

The invention relates to a tool for use in moving railroad ties to properly space them under the rails, and has for its object the provision of a device including a lever fulcrumed on a rod carrying a rail gripping member that is so constructed that in moving the lever in one direction the gripping member will be released from engagement with the rails to slide thereon, while moving the lever in an opposite direction will cause the member to grip the rail thus forming a fulcrum for the lever.

The invention will be described in detail hereinafter and will be found illustrated in the accompanying drawings in which:—

Figure 1 is a side view showing the improved railroad tie spacer as applied to a railroad rail and tie,

Figure 2 is a top plan view of the implement, and

Figure 3 is a detail of the rail gripping member.

In the drawings similar reference characters will be used to designate corresponding parts throughout the several views.

The railroad tie spacer comprises a lever 1 having a rod 2 pivotally secured thereto by means of a bifurcated end 3. Rod 2 has its free end secured to a slotted head 4, and pivotally mounted in the slotted head 4 is a rail gripping member 5 by means of pivot pin 6. Rail gripping member 5 is provided

with downwardly extending spaced flanges 7 forming a U-shaped member to the tread of the railroad rail A and to grip the sides of the tread when the lever 1 is moved outwardly and downwardly to engage a tie and provide holding means for the rod 2 to fulcrum the lever 1. A lug 8 extends laterally of one side of the member 5 and by engaging the slotted frame 4 when the lever is moved in the opposite direction serves to release the flanges 7 from gripping position and permit the U-shaped gripping member to ride on the rail to assume another position to grip the rail when the lever is moved in the first mentioned direction again.

The construction and operation of the invention will be apparent from the copy of the drawings and the above description and a further description is considered to be unnecessary.

What is claimed is:—

A railroad tie spacer, comprising a lever adapted to engage a tie, a rod pivotally engaging said lever, a slotted head on said rod, a U-shaped member pivotally secured in said head, and a stop on said U-shaped member to limit the pivotal movement thereof in one direction, said U-shaped member being adapted to seat on a railroad rail and grip it during one movement thereof.

In testimony whereof I affix my signature.

GEORGE F. DICKS.
